His ATTORNEY.

UNITED STATES PATENT OFFICE.

CLINTON O. HARRINGTON, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

1,343,719.

Specification of Letters Patent. Patented June 15, 1920.

Application filed April 17, 1918. Serial No. 229,001.

To all whom it may concern:

Be it known that I, CLINTON O. HARRINGTON, a citizen of the United States, residing at Swissvale, in the county of Allegheny and 5 State of Pennsylvania, have invented certain new and useful Improvements in Relays, of which the following is a specification.

My invention relates to electromagnetic relays, and has for an object the provision 10 of a relay of this type wherein the windings are placed as close as possible to the pole-pieces of the electromagnet, while the usual features of insulation are maintained in so far as concerns the terminal posts of 15 the relay.

I will describe one form of relay embodying my invention and will then point out the novel features thereof in claims.

In the accompanying drawings, Figure 1 20 is a view showing in side elevation one form of relay embodying my invention. Fig. 2 is a top plan view of the relay, partly sectioned on the line II—II of Fig. 1. Fig. 3 is a fragmental sectional view taken on the 25 line III—III in Fig. 2.

Similar reference characters refer to similar parts in each of the views.

Referring now to the drawings, the relay, in the form here shown, comprises a cylindrical box-like structure made up of a bottom plate 1, a glass ring 2 forming the sides of the box, and a top plate 3. The operating parts of the relay are inclosed within this box-like structure, and are supported by the 30 top plate 3, which plate I will therefore term the "supporting member" of the relay. This member is of insulating material, such as porcelain, hence it must be relatively thick to provide the necessary strength. The 35 top plate 3, which plate I will therefore term the "supporting member" of the relay. This member is of insulating material, such as porcelain, hence it must be relatively thick to provide the necessary strength. The 40 terminal posts 4, connected with the relay contacts, are mounted in this supporting member 3 in the usual manner.

The supporting member 3 is provided with an elongated aperture 5, shaped somewhat 45 as shown in Fig. 2, which aperture is large enough to accommodate both coils of the relay with ample clearance. The aperture 5 is covered by a relatively thin non-magnetic metal plate 6 which rests against the 50 under surface of member 3 and is fastened to this member by screws 7. The plate 6 carries the electromagnet which comprises, as usual, a pair of soft iron cores 8, a pole-piece 9 at one end of each core, a back strap 55 10 uniting the cores at the other end, and a

coil 11 on each core. The cores 8 pass through suitable holes in the plates 6, and the pole-pieces rest against the under surface of this plate while the coils rest against the upper surface thereof. It will be seen, 60 therefore, that the coils are brought very close to the pole-pieces, being separated therefrom only by the thickness of the plate 6.

The cores of the electromagnet may be attached to plate 6 in any desired manner. As here shown, each core is threaded for a short distance near the pole-piece and is screwed into the hole in plate 6 through which the core passes, this hole being threaded for the 70 purpose. The threads on the core, which are designated 13, are of greater diameter than the remainder of the core, so that the core slides freely through the hole up to the threaded portion. The core may be prevented from turning, if desired, by passing a dowel pin through the pole-piece and into the plate 6 after the core has been screwed into place in the plate.

In order to simplify the drawing, I have 80 omitted the armature which is controlled by the electromagnet, and the contacts which in turn are controlled by the armature, these parts being of usual construction and forming no part of my invention.

By virtue of the construction thus described, I am enabled to retain the usual "top plate" 3 of insulating material, in which the terminal posts 4 may be mounted without concealed insulation, and yet I am 85 enabled to bring the magnet coils much closer to the pole-pieces than is the case when the magnet is mounted directly on the plate or supporting member 3. This close relation of the coils and pole-pieces, of course, 90 improves the efficiency of the relay.

Although I have herein shown and described only one form of relay embodying my invention, it is understood that various changes and modifications may be made 100 therein within the scope of the appended claims without departing from the spirit and scope of my invention.

Having thus described my invention, what I claim is:

1. A relay comprising a relatively thick supporting member of insulating material in which the terminal posts are mounted, said member having an aperture there-through of sufficient size to accommodate 110

the magnet of the relay, a relatively thin metal plate attached to said supporting member and covering the aperture in the latter, the magnet being mounted in said plate with its pole-pieces on one side thereof and its coils on the other side.

2. A relay comprising a relatively thick supporting member of insulating material in which the terminal posts are mounted, 10 said member having an aperture therethrough, a relatively thin metal plate attached to said supporting member and cov-

ering the aperture in the latter, and an electromagnet mounted in said metal plate with its cores passing therethrough, the pole-pieces abutting against one surface of said plate and the windings abutting against the other surface.

In testimony whereof I affix my signature in presence of two witnesses.

CLINTON O. HARRINGTON.

Witnesses:

A. HERMAN WEGNER,
FAY GLASGOW.
